Application May 9, 1945, Serial No. 592,787

3 Claims. (Cl. 230—207)

1

This invention relates to means for lubricating pumps of the type that pump air and other gases; and particularly to lubricating means actuated by pump produced vacuum.

The lubricating means described herein is applicable to pumps of various types and as used for various purposes; and illustrative thereof is the pumping unit disclosed in the co-pending application of Ervin J. Osterhus, Serial Number 591,323, filed May 1, 1945, to which is applied a lubricator similar to that of the present invention.

According to the present invention, the vacuum developed at the intake side of an air or like pump is utilized to actuate a lubricator and draw lubricant such as oil into the pump.

This principle in general has been utilized heretofore; but in all such prior arrangements of which I have knowledge the amount of oil or rate of feeding of it to the pump varies with the amount of vacuum drawing it in; and if the rate of lubricant feed is set so as to be sufficient at low pump vacuum, it is excessive at high vacuum, and if it is set to be correct for high vacuum it is insufficient at low vacuum.

According to another prior practice, pump lubricating oil is supplied from a reservoir by a metering arrangement continuously supplying oil, drop by drop for example, at a measured rate; but, in such arrangements, the feeding of oil goes on even after the pump is stopped, and therefore will flood the pump and uselessly deplete the oil supply, unless care and attention is exercised to cut the feed on and off as the pump is used intermittently.

It is desirable for various reasons to feed lubricating oil or the like to the pump at a constant but adjustable rate at all times and independent of the degree of vacuum developed by the pump; and that it shall be supplied only when the pump is operating and automatically cease to be supplied when the pump stops.

It is the object of the invention to provide a pump lubricating means having the above described desirable mode of operation.

Other objects will be apparent to those skilled in the art to which the invention appertains.

The invention is fully disclosed in the following description taken in connection with the accompanying drawing, in which:

Fig. 1 is a longitudinal section view of a pump with which the invention may be used, and showing one embodiment of the invention associated therewith, the parts of the pump being illustrated somewhat diagrammatically for simplicity:

2

Fig. 2 is a cross sectional view taken from the plane 2 of Fig. 1, with parts behind the section plane omitted for simplicity, to show more clearly a clamping and adjusting device of Fig. 1;

5 Fig. 3 is a view similar to a part of Fig. 1 and illustrating a modification of the lubricating means of that figure.

Referring to Fig. 1, the pump shown generally at 1 has internally thereof a cylindrical chamber 10 10 2 against the wall of which eccentrically supported pump vanes 3—3 engage in a well known manner as they are rotatably driven by a shaft 4. The pump has an outer wall 5. Partitions 6 and 7 provide a vacuum chamber 8 with which 15 communicates an intake passage 9 into which a conduit may be screwed; and the construction provides also an output or pressure chamber 10 into which a conduit may be screwed at 11. Whatever may be the uses of the pump, it is contemplated that during its operation vacuum will 20 be developed in the chamber 8 and that this vacuum will be of different degrees at different times.

A recess 12 is provided at one point of the 25 cylinder wall 2. A tube 13 extends into a bore 14 in the cylinder wall and communicates with the recess. The tube has an enlarged head 15 threaded into the outer wall 5 of the pump housing, and the tube 13 has perforations 16 in its 30 wall surrounded by a screen or like filter 17.

A pipe elbow 18 is threaded into the head 15. A plug 19 is screwed at one of its ends into the open end of the elbow 18 at 20, and at the other end projects into the tube 13. This plug has a 35 bore 21 opening into the elbow 18 and at the opposite end is closed except for a small hole 22, which as an illustrative case, may be the size of a No. 50 drill.

An elbow 23 is threaded into the outer end of 40 the elbow 18. Into the outer end of the elbow 23 is threaded a tubular shank 24 of an oil pot 25, or chamber, the shank preferably extending approximately horizontally.

The pot or chamber 25 has an upwardly extending neck 26. A tubular clamp 27, slotted at one side as at 28, is clamped around the neck 26 by a screw 29 and two ears 30 on the clamp, see also Fig. 2. A reservoir carrier is provided comprising a head 31 resting upon the clamp 27, 50 and a tubular internally threaded flange 32 extending upwardly from the head, and an open tube 33 extending downwardly from the head and through the neck 26 and into the pot 25.

An oil supply reservoir 34 in the form of an 55 inverted cup, and preferably being of glass to

render it transparent so that the supply of oil therein may be inspected, is threaded at its lower end into the flange 32 and sealed on the head 31 at its downwardly open end by a gasket 35. The lower end of the tube 33 is preferably cut off at an angle as shown.

With the arrangement thus far described, oil in the reservoir 34 will flow into the pot 25, shank 24, and elbow 23 and air will take its place in the reservoir until the oil rises to the level of the lower open end of the tube 33 as shown; and as oil is drawn out of the pot during operation to be described, oil is supplied to it from the reservoir 34, and the level of the oil is thus continuously maintained constant in a well known manner; and the height of the level may be adjusted by adjustably raising or lowering the lower end of the tube 33 by raising or lowering the clamp 27, by which it is supported.

The elbow 18 has a large hole 36, for example $\frac{1}{4}$ inch in diameter, in its rear wall.

At 37 is an elongated piece of oil absorbing porous material; and because of the practicability, convenience, and cheapness thereof, I prefer to use for this purpose a length of ordinary tobacco pipe cleaner, which as is well known comprises a central wire core surrounded by a mass of fibrous absorbent material. While other material may be used for this purpose, pipe cleaner material is preferred, but for convenience of description will hereinafter be referred to as porous material.

The porous material 37 extends from the bore 21 of the plug 19, through the elbows 18 and 23, into the shank 24, or through the shank and into the pot 25.

The apparatus is preferably assembled in the following manner. One end of the porous material 37 is inserted into the bore 21 of the plug 19. The reservoir shank 24 and the two elbows 18 and 23 are all three screwed together. The free end of the porous material 37 is then inserted into the small end of the elbow 18 and fed therethrough, and the plug 19 is then screwed into the elbow 18. The elbow 18 is then screwed into the tube head 15.

In operation, the lower end portion of the porous material 37 always lies in, or below the level of, the oil in the shank 24 and therefore absorbs oil. By capillary action the oil rises in and along the porous material up into the elbow 18.

When the pump is working, vacuum is created within the chamber 8 and within the tube 13, and air flows in at the elbow opening 36 and flows over the oil-wet porous material 37 and into and through the bore 21 of the plug 19, through the small hole 22 in the plug, and into the tube 13, and thence to the pump chamber 2.

The bore 21 in the plug and the outside diameter of the porous material 37 are proportioned so that the presence of the porous material in the bore does not prevent the flow of air or air and oil through the plug. This flow of air as described, picks up oil from the oil-wet porous material 37 and carries it through the tube 13 to the pump.

The hole 36 in the elbow 18 is so much larger than the hole 22 in the plug 19, that no appreciable vacuum develops in the elbow 18 regardless of how high a vacuum may be developed by the pump. One result of this is that there is a flow of air through the elbow 18 and over the oil-wet porous material 37 in it, substantially at atmospheric pressure; and consequently the level of the oil in the shank 24 and pot 25 is not af-

fected or changed by the developed vacuum, but remains constant at all degrees of vacuum.

The length of that portion of the porous material 37 above the oil level, is therefore constant, because the oil level is constant; and the force of capillarity being a constant, oil creeps up along that part of the porous material 37 in the elbows 23 and 18 at a constant rate.

The flow of air through the elbow 18 and through the small hole 22 in the plug, even at low vacuum, would obviously be able to carry oil over into the pump at a high rate if there were a sufficiently ample oil supply, in the line of air flow, but it cannot carry it over at a rate greater than that at which the porous material supplies it, which is at a constant rate, hence at low, high, and intermediate vacuum the rate of oil supplied to the pump is constant.

Also, as will now be apparent, the rate of oil supplied to the pump can be adjustably changed when desired by adjustably changing the oil level as described. If the oil level is raised, the oil traveling up the porous material 37 into the elbow 18 has a shorter distance to travel by capillarity, and hence covers this distance in a shorter time and therefore supplies oil at a higher rate.

The lubricating apparatus therefore supplies lubricant to the pump at a rate which is adjustable, but, when adjusted, is independent of the degree of vacuum in the pump.

When the pump stops working, the vacuum actuating the lubricator disappears; and the porous material remains oil-wet; but no oil is carried therefrom into the pump because the flow of air over it ceases. Means to cut off the oil supply when the pump stops and to turn it on again when the pump is to be operated is therefore unnecessary.

In Fig. 3 is illustrated another structure in which the above described lubricating principles may be embodied and which form may in some cases be preferred.

In this figure, some of the parts of Fig. 1 are reproduced. A fragment of the pump of Fig. 1 is shown, as well as the tube 13 having the head 15 described for Fig. 1. A nipple 38 is provided, threaded at its opposite ends and having intermediate thereof a wrench receiving head 39 for turning it. One end of the nipple is closed as at 40 except for a small hole 41 which as in the form of Fig. 1 may be of a size corresponding to a No. 50 drill, and this closed end is screwed into the head 15 at 43. The other end of the nipple 38 is screwed as at 44 into a housing 45 and communicates interiorly therewith.

The housing 45 is generally in the form of an elbow and its outer or lower end portion 46 is internally threaded as at 47 to receive an exteriorly threaded oil reservoir 48 of glass or other transparent material sealed to the housing by a gasket 49.

Within the elbow housing 45 and carried thereby is the following structure. A tube 50, which may be of copper or other metal, and generally vertically disposed, extends through a bore 51 in the wall of the housing 45 and is open to the atmosphere at its upper end as at 52 and is soldered or otherwise secured to and sealed to the housing by solder or the like at 53.

The tube 50 extends downwardly through and below the lower end of the housing 45 whereby its lower end will be disposed in, and near to the bottom of, the reservoir 48 in its mounted position, and therefore immersed in the supply of oil 54 contained in the reservoir. At its lower

end, the tube 50 extends horizontally as at 55 and joins a riser tube 56, the riser tube at its lower end being closed except for a small drilled opening 57.

The riser tube 56 extends upwardly and out of the oil 54 and at its upper end, as at 58, is bent inwardly and over the side wall 59 of a metal cup indicated generally at 60.

The cup 60 is upwardly open and the aforesaid tube 50 extends through the cup bottom through a suitable perforation therein, and the juncture is preferably sealed, for example, by solder 61.

The cup bottom is provided with a downward extending tubular portion 62 closed at its lower end.

A length of pipe cleaner porous material 63, as identified and described in connection with Fig. 1, has one end thereof projecting into the cup bottom extension 62 to support and position it, and above the cup 60 it extends upwardly through the elbow housing 45 and its other end lies in the interior of the nipple 38.

The operation of this form of the lubricator is as follows. When vacuum is produced by the pump in the chamber 8 and tube 13, atmospheric air flows into the pipe 50 at its open end 52, through this pipe and upwardly through the riser tube 56 and out at its discharge end 58 into the interior of the housing 45, whence it flows through the nipple 38 and through the small hole 41 into the tube 13 and into the pump.

The internal size of the pipes 50, 55, and 56 through which the air flows may be so large compared with the size of the little hole 41 in the nipple 38 that development of vacuum in the housing 45 may be completely prevented by the flow of air thereinto through said pipes. The interior of the housing 45 may thereby be maintained at all times substantially at atmospheric pressure, whether the pump-developed vacuum is high or low or intermediate. But in this form of the invention it is not essential to have atmospheric pressure in the housing 45 because the change of pressure cannot change the oil level in the cup 60; so that the relative sizes of the pipes and the hole 41 is not critical; and the device will operate satisfactorily if the pipes are large enough to supply a sufficient flow of air to effect lubrication as described. For a hole 41 of the size of a No. 50 drill, pipes $\frac{1}{16}$ inch to $\frac{1}{8}$ inch internal diameter will suffice.

In the drawing the oil 54 is shown as filling the lower part of the pipe line, 50—55—56, this being the normal or idle condition, and the air flowing as described, displaces the oil, causing it to flow out of the pipe 56 at the orifice 58 and into the cup 60.

As the flow of air upwardly through the riser tube 56 continues, it draws oil into it through the orifice 57 and continuously discharges it together with the air at the discharge outlet 58 into the cup 60 and fills the cup and maintains it full of oil, the excess overflowing from the cup back into the reservoir 54. By this means, a level of oil in the cup 60 is maintained at a constant distance below the nipple 38.

The porous material 63 picks up oil from the cup 60 by capillarity and it rises up and along the material in the housing 45.

The flow of air through the housing 45 and through the nipple 38 flows over the oil-wet porous material 63 and picks up oil therefrom and carries it on through the small hole 41 into the tube 13 and into the pump.

The distance which the oil must creep up

along the pipe cleaner material 63 is at all times constant and does not vary with withdrawal of oil 54 from the reservoir 48, because this distance is determined by the level of the oil in the cup 60 which is at all times constant.

In this form, as in the form of Fig. 1, the rate of oil feed to the pump is constant being determined by the vertical distance over which oil travels by capillarity in the porous material 63.

While the two forms of the invention (Fig. 1 and Fig. 3) differ in appearance, they have features in common, respectively. They each have a refillable oil reservoir 34 and 48; and a receptacle 24 and 60 in which oil is maintained at a constant lower supply level; a porous capillary element 37 and 63 contacting the oil at said level and raising oil by capillarity to a higher level. Each form has a walled enclosure which contains the oil and keeps it from spilling out due to any cause and from becoming contaminated by foreign matter. Each form has a substantially unrestricted atmospheric-air-inlet 36 and 52 to the enclosure, and an air flow restriction 22 and 41 between the enclosure and the vacuum pump chamber; and the upper-level portion of the porous capillary element is disposed so that air flowing from the enclosure to the vacuum chamber flows over it.

The restrictions 22 and 41 are small enough not to interfere with the development of the maximum desired useful vacuum in the pump; but at the same time allow air to flow over the upper portion of the oil-wet porous capillary element, even at low vacuum, at a rate great enough to carry away the oil from it as fast as it raises the oil by its capillarity. Hence in both forms for a given oil supply level and a given length of capillary element above the oil supply level, the rate at which oil is supplied to the pump is constant at all degrees of vacuum. In both forms, the feed of oil to the pump stops when the pump stops working and ceases to develop vacuum.

My invention is not limited to the exact details of construction shown and described but comprehends all changes and modifications that come within the scope of the appended claims.

I claim:

1. A lubricator for an air pump having a vacuum chamber, comprising: an oil-containing walled enclosure; means to maintain oil in the enclosure at a constant predetermined level; a capillary element having a lower portion contacting the oil and an upper portion to which it raises oil by capillarity to a level above the predetermined level; an air flow conduit communication between the interior of the enclosure and the pump vacuum chamber; an air flow restriction in said conduit communication; a substantially unrestricted atmospheric air inlet to the enclosure interior; whereby vacuum developed in the pump vacuum chamber causes air to enter the enclosure at the air inlet and flow out of the enclosure to the chamber through the restriction; and the said upper portion of the capillary element being disposed in the line of air flow between the enclosure interior and the restriction.

2. A lubricator for a pump having a vacuum chamber, comprising: a walled enclosure; a capillary element in the enclosure disposed to have an upper and a lower portion; means to maintain a supply of oil in the enclosure and on the lower portion of the capillary element, at a preselected constant elevation thereon; the capillary element adapted to raise oil from the lower to the upper portion by capillarity; conduit means providing

an air flow passageway directly from ambient atmospheric air to the vacuum chamber and through which vacuum in the vacuum chamber causes air to flow; and the upper portion of the capillary element being disposed in the line of the air flow.

3. A lubricator for a pump having a vacuum chamber, comprising: a walled passageway communicating at one end with the vacuum chamber; a walled enclosure communicating with the other end of the passageway; a substantially unrestricted air flow inlet to the enclosure; an air flow restriction in the passageway; the enclosure comprising an oil receptacle; an oil reservoir above the receptacle; means comprising a gravity supply tube communicating with the receptacle and reservoir, and maintaining a constant oil level

in the receptacle; a porous, elongated capillary element having a lower end portion in the oil of the receptacle, and extending upwardly therefrom, and at its upper end portion projecting into the passageway between the restriction and the air flow inlet.
